UNITED STATES PATENT OFFICE.

WILLIAM H. TIERNEY, OF WASHINGTON, DISTRICT OF COLUMBIA.

SWING.

Application filed March 10, 1926. Serial No. 93,710.

This invention relates to swings and more especially to a mechanical movement whereby by the occupant of a swing, by the exertion of comparatively slight power can maintain an oscillation of the swing.

A further object is to provide a swing having a shiftable fulcrum supported by anti-friction means, simple and effective mechanism being used for changing the position of the fulcrum so as to cause the swing to oscillate about the moving fulcrum.

Another object is to provide a means operated by the oscillation of the swing for aiding the operator in actuating the mechanism so as to reduce to the minimum the energy required to maintain the swing in motion.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a front elevation of a swing embodying the present improvements.

Figure 2 is a section on line 2—2 Figure 1.

Figure 3 is a section on line 3—3 Figure 1.

Figure 4 is a section on line 4—4 Figure 3 showing one of the adjustably mounted tripping arms.

Referring to the figures by characters of reference 1 designates a supporting structure which can be of any desired construction. This structure includes spaced ledges 2 cooperating to form a track on which are mounted wheels 3 journaled on the ends of an axle 4. Secured to the axle at opposite sides of the center thereof are sleeves 5 each of which is provided, at one end, with an annular flange 6 from which is extended a tripping arm 7 and the two tripping arms are extended substantially in opposite directions as shown in Figures 2 and 3. A hanger 8 is mounted on each sleeve 5 so as to rotate thereon and attached to each hanger is an angular bracket 9 which is also fitted on sleeve 5 and adapted to rotate thereon. These brackets constitute means

for preventing the hangers 8 from swaying laterally while the swing is in use. The two hangers serve to support a seat 10 which can be of any construction desired.

The middle portion of axle 4 is enlarged as shown at 11 and has an opening 12 extending therethrough the wall of which is screw threaded for engagement with the threaded portion 13 of an actuating shaft 14 extending through the enlargement 11 at right angles to the longitudinal axis of the axle 4. Shaft 14 is journaled in hangers 15 depending from the top 16' of the supporting structure and secured to or formed on this shaft close to each of the hangers is a gear 16. A segmental gear 17 having a radial arm 18 is journaled on one of the hangers 15 and meshes with one of the gears 16 while another segmental gear 19 is journaled on the other hanger 15 and meshes with the other gear 16, this segmental gear 19 being provided with a radial arm 20. As shown particularly in Figures 1 and 3 the arms 18 and 20 extend substantially in opposite directions, arm 18 cooperating with one of the tripping arm 7 as hereinafter explained while arm 20 cooperates with the other arm 7.

A pulley 21 is secured to one end of the shaft 14 and another similar pulley 22 is secured to the other end of said shaft. An actuating rope 23 is secured to the pulley 21 and is extended one or more times therearound. From this pulley the said rope is extended over guide pulleys 24 mounted on the top 16' and thence downwardly to a point close to the seat 10 where it can be grasped readily by the occupant. Another rope 25 is secured to and wrapped about the other pulley 22 and is extended over a guide pulley 26 mounted on the top 16' from which it hangs so that the end thereof is supported close to the seat 10.

The normal position of the axle 4 is midway between the ends of the ledges 2. When it is desired to actuate the swing the occupant of the seat 10 pulls on one of the ropes. If rope 25 is pulled it will be partly unwound from its pulley 22 and cause shaft 14 to rotate in one direction. Thus the rotating threaded portion 13 will shift the axle 4 and cause the rollers 3, which support the weight of the occupant, to travel toward one end of the track formed by the ledges. The seat 10 will thus be caused to swing in the same direction in which the

- axles has moved and as it reaches this limit of its swinging movement the operator, by pulling on the cord 23, can reverse the rotation of shaft 14 and cause the threaded portion 13 to shift the axle 4 toward the other end of the track. Thus the swing will be caused to move in the opposite direction and by intermittently pulling upon the ropes in proper succession and at proper intervals a steady oscillation of the swing can be produced. By providing the tripping arms 7 and the radial arms 18 and 20 it is possible to impart automatically an impulse to the axle at the beginning of each movement thereof. For example, as the swing reaches one limit of its swinging movement the advancing arm 7, which moves with the swing, will come against the arm 18 and force it upwardly. Thus the meshing gears 17 and 16 will act to reverse the rotation of shaft 14, the reverse movement being supplemented by a pull upon the proper rope by the operator. The stopping and slight reversal of the movement of the axle due to the coaction of arms 18 and 20 with the arms 7 acts as a signal by which the operator is governed in pulling upon the ropes. It will be obvious that, as the weight of the load is carried by the wheels 3 which constitute anti-friction devices, and the shifting of the axle is affected by the rotation of the threaded shaft 14, very little power is required to actuate the swing.
35. For the purpose of properly adjusting the arms 7 for cooperation with the respective arms 18 and 20, said arms may be held to the brackets 9 by bolts 27 extending through the arms and each of which is adapted to be positioned in any one of a series of apertures 28 formed in the adjacent bracket 9.
- What is claimed is:
1. The combination with an axle and anti-friction means for supporting the same for bodily movement, of a swing suspended from the axle, and means for imparting a back and forth motion bodily to the axle to start the oscillation of the swing.

2. The combination with a wheel supported axle, of a swing suspended therefrom, means independent of the swing for imparting a back and forth movement to the axle for oscillating the swing, and means actuated by the swing during the completion of each oscillation for reversing the action of the axle moving means.

3. The combination with an axle mounted for bodily movement at right angles to its longitudinal axis, of a swing suspended from the axle, and means independent of the swing for imparting a back and forth motion bodily to the axle to oscillate the swing.

4. The combination with an axle mounted for bodily movement, of a swing suspended therefrom, means operated by the occupant of the swing for reciprocating the axle at right angles to its longitudinal axis to start the oscillation of the swing.

5. The combination with an axle mounted for bodily movement and anti-friction supporting means therefor, of a swing suspended from the axle, a threaded shaft extending at right angles to and operatively connected to the axle, and means for imparting a back and forth rotation to said shaft to reciprocate the axle and oscillate the swing.

6. The combination with an axle mounted for bodily movement and anti-friction supporting means therefor, of a swing suspended from the axle, a shaft having a threaded portion for shifting the axle bodily at right angles to its longitudinal axis, means for imparting a back and forth rotation to said shaft to reciprocate the axle and oscillate the swing, separate tripping means movable with the swing and separate means cooperating with the respective tripping means for imparting a reverse motion to the shaft during the completion of each oscillation of the swing.

In testimony that I claim the foregoing as my own, I have hereto affixed my signature.

WILLIAM H. TIERNEY.
